RANGE

Filed Oct. 23, 1937

UNITED STATES PATENT OFFICE

2,175,159

RANGE

Frank H. Schneider, Royersford, Pa., assignor to
 The Floyd-Wells Company, Royersford, Pa., a
 corporation of Pennsylvania

Application October 23, 1937, Serial No. 170,536

2 Claims. (Cl. 126—42)

The object of this invention is to devise novel controlling mechanism for the oven vent damper and the fuel supply to an oven burner and a broiler burner whereby the fuel supply control 5 cannot be operated to supply fuel to either the oven burner or to the broiler burner until the vent damper has been moved into its open position.

A further object of the invention is to devise novel means independent of the fuel control for 10 actuating the vent damper.

A further object of the invention is to devise separate means for actuating the vent damper control and the fuel control, the controls being constructed and arranged in such a manner that 15 when the vent damper is closed the vent damper control will lock the fuel control in its inoperative or "off" position.

My present invention, although not limited to such use, is especially adapted to be employed 20 in ranges having an oven, flue and burner arrangement constructed in accordance with my prior Patent No. 2,089,816, of August 10, 1937, and in which two different types of fuel can be employed for heating the oven.

25 With the above and other objects in view as will hereinafter clearly appear, my invention comprehends a novel range having novel controlling mechanism for the oven vent damper and for the fuel supply which is selective to supply fuel to an oven burner or to a broiler burner, and wherein the vent damper must be moved to open position before the control for the fuel can be operated to supply fuel to either the oven burner or the broiler burner.

30 It further comprehends a novel controlling mechanism wherein the fuel control is locked in its neutral position by the control for the oven vent damper.

35 Other novel features of construction and 40 advantage will hereinafter more clearly appear in the detailed description and the appended claims.

For the purpose of illustrating the invention, I have shown in the accompanying drawing a 45 typical embodiment of it, which, in practice, will give satisfactory and reliable results. It is, however, to be understood that the various instrumentalities of which my invention consists can be variously arranged and organized, and 50 my invention is not limited to the exact arrangement and organization of these instrumentalities as herein set forth.

Figure 1 is a sectional elevation of a range embodying my invention.

55 Figure 2 is a front elevation of the fuel con-

trolling means and the damper actuating member.

Figure 3 is a sectional elevation showing more particularly the fuel supply control and a portion of the damper actuating means. 5

Figure 4 is a top plan view of the construction seen in Figure 3 with the front wall of the range in section.

Figure 5 is a side elevation showing a portion 10 of the damper and its operating means.

Similar numerals indicate corresponding parts.

Referring to the drawing:

1 designates a range embodying my invention.

The construction and arrangement of the combustion chamber for coal and oil, the oven burner, 15 the oven, and the coal and gas flues is similar to that disclosed in my prior Patent No. 2,089,816, of August 10, 1937, and since this construction has been on the market for some time and is now well known in this art, a detailed illustration 20 and description is believed to be unnecessary. I will therefore explain such construction only in sufficient detail for a clear description of the operation, reference being directed to my herein identified prior patent. 25

The oven 2 is heated, either independently or simultaneously by a source of heat (not shown) such as coal or oil, or by an oven burner 3. The oven is provided with a broiler burner 4 preferably located in the upper part of the oven 2. 30 The oven has a vent opening 5 controlled by an oven vent damper 6 slidably mounted along side of the vent opening. The vent opening 5 leads into an open ended casing 7, the ends of which open into the room in which the range is located. 35 The casing 7 vents into the main discharge flue 8 through a vent opening 9 controlled by a damper 10 connected at 11 to the oven vent damper 6 so that the two dampers move in unison. 40

The vent damper 6 has its own independent manual control which must be operated to move the vent damper to open position before fuel can be supplied to either the oven burner or to the broiler burner. 45

The front wall of the range has secured to it a plate 12 having an outwardly extending annular flange 13 with which a damper actuating member 14 is in telescopic relationship. The member 14 is preferably cup shaped and has 50 welded or otherwise secured to its rear wall, rods 15 which pass through the front wall of the range and are provided with means such as nuts 16 which limit the outward movement of the actuating member 14. The rods 15 are en- 55

circled by springs 17 which tend to move the actuating member 14 outwardly. A rod 18 has one end in the path of movement of the actuating member 14 and its opposite end is connected with 5 one end of a lever 19 fulcrumed at 20 to a stationary portion of the range. The opposite end of the lever 19 is connected by a link 21 with one end of a lever 22 fulcrumed at 23 to a stationary portion of the range. The opposite 10 end of the lever 22 is connected by a link 24 with the oven vent damper 6. A spring 25 connected at one end to the oven vent damper 6 and at its opposite end to a fixed portion of the range tends to move the oven vent damper into 15 its closed position.

26 designates a two way fuel control valve having a pipe 27 leading to the oven burner and a pipe 28 leading to the broiler burner. The fuel valve 26 has an actuating handle 29 and the 20 damper actuating member 14 has an opening 30 into which the valve handle 29 extends when the oven vent damper is in its closed position. It will thus be evident that the fuel valve cannot be moved to supply fuel to either the oven burner 25 or to the broiler burner until the actuating member 14 has been pressed forwardly sufficiently to clear the valve handle and permit its partial rotation in one direction or the other. The fuel valve 26 is provided with a fuel inlet 31 in communication with a source of fuel supply.

The operation will now be clear to those skilled in this art and is as follows:—

The valve handle 29 of the fuel valve is turned in one direction to supply fuel to the oven burner 35 and is turned in the opposite direction to supply fuel to the broiler burner. The operator can use the same hand which he uses to operate the fuel supply valve to operate the actuating member for the oven vent damper.

40 If now the operator desires to supply fuel to a selected burner, he first pushes inwardly the damper actuating member 14, which, pressing against the rod 18, actuates the linkage for the damper to move the damper into open position. 45 Since the damper actuating member 14 has now been moved forwardly beyond the inner face of the valve handle 29, such valve handle can be turned in the proper direction to supply fuel to a selected burner.

50 The turning of the fuel valve handle 29 in either direction will retain the damper actuating member 14 in its inward position, and, thereby, the oven vent damper in its open position. When the valve handle is returned to its neutral position the 55 springs cause the valve actuating member 14 to move outwardly, so that the valve handle will extend into or through the opening 30, and the

walls of such opening 30 will prevent the turning of the valve handle from its neutral position.

When the damper actuating member 14 is moved forwardly, it moves forwardly the rod 18 thereby turning the lever 19 on its fulcrum. This 5 actuates the link 21 to turn the lever 22 in a direction to cause the link 24 to move the oven vent damper 6 into its open position. The spring 25 returns the oven vent damper to closed position when the fuel valve is returned to its neutral 10 position.

The springs 17 return the damper actuating member to its neutral position and retain it in such neutral position when the fuel control valve has been returned to its neutral position.

Having thus described my invention, what I 15 claim as new and desire to secure by Letters Patent is:

1. The combination with a wall of a range, of 20 telescopic members having limited relative movement, one of which is secured to said wall and the outer of which has a slot to prevent turning of a grasping portion of a valve handle, a valve handle extending through said wall and having its grasping portion in said slot when the valve 25 is closed, means tending to move said outer member into a position to receive said grasping portion and prevent its turning, and a rod adapted to be connected to a member to be actuated and having an end contacting at all times said outer 30 member to be moved when said outer member is moved to release the grasping portion of said valve handle and said valve handle when turned engaging said outer member to retain it in its forward position and thereby said rod in its forward 35 position.

2. The combination with a wall of a range of 40 an inner member and an outer member in telescopic relationship, the inner member being fixed to said wall, the outer member having a slot into which the grasping portion of a valve handle extends to prevent turning of the valve handle, a rod extending from said outer member through said wall and having means to prevent its withdrawal through said wall, a spring between said 45 outer member and said wall, an actuating member moved inwardly by said outer member when the latter is moved inwardly to release the grasping portion of the valve handle said valve handle when turned riding on the outer face of said outer member to retain the latter and thereby said actuating member in their forward positions, and a spring to maintain said actuating member at all times in contact with said outer telescopic member.

FRANK H. SCHNEIDER.
